(74) *Attorney, Agent, or Firm* — Bochner PLLC; Andrew D Bochner(57) **CLAIM**

The ornamental design for an edible lid, as shown and described.

DESCRIPTION

FIG. 1 is a perspective view of an edible lid;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a perspective view of the edible lid, showing use thereof.

In the drawings, the broken lines are for the purpose of illustrating environment only, and form no part of the claimed design.

1 Claim, 7 Drawing Sheets(56)
